UNITED STATES PATENT OFFICE.

LEON PIERCE, OF NEW YORK, N. Y., ASSIGNOR TO THE UNDERPINNING & FOUNDATION CO., OF NEW YORK, N. Y., A CORPORATION OF NEW YORK.

APPARATUS FOR FORMING CONCRETE CAPS ON PILES.

1,072,491.

Specification of Letters Patent.

Patented Sept. 9, 1913.

Application filed April 15, 1912. Serial No. 691,067.

To all whom it may concern:

Be it known that I, LEON PIERCE, a citizen of the United States, residing at the borough of the Bronx, in the city, county, and State 5 of New York, have invented certain new and useful Improvements in Apparatus for Forming Concrete Caps on Piles, of which the following is a specification, reference being had to the accompanying drawings.

10 This invention relates to improvements in apparatus for forming caps of cementitious material on piles; and an object of this invention is the provision of a simple, cheap and efficient apparatus for accomplishing 15 the formation of such caps.

Another object of this invention is to avoid the expense of making an excavation for the capping and of trenching down to water level, where wooden piles are ordinarily cut off.

20 In the drawings illustrating the principle of this invention and the best mode now known to me of applying that principle, Figure 1 is a central longitudinal vertical 25 section through the follower, which is shown mounted upon the pile; Fig. 2 illustrates the manner in which a concrete cap is formed upon a pile above water level, the follower being shown partly withdrawn; and Fig. 3 30 is a view similar to Fig. 2 and illustrates the method of forming a concrete cap upon a pile under water.

The body portion of the follower *a* consists of a pair of tubular members *b*, *c*, one 35 of which is arranged concentrically within the other, whereby the body portion is made hollow and is formed with a central bore *d*. Suitably joined to the body portion at its 40 upper end is the follower head *e*; and the lower end of the follower is provided with the base member *f*, which is shaped to receive the upper end of the pile *g* which fits snugly therein. Of course, the number of 45 parts of which the follower consists is immaterial, as are also the particular substance of which these parts are made and the manner in which they are joined or held together. Any mechanic may by merely exercising the skill of his calling select the 50 proper material from which to build up the parts and may without invention devise a

suitable method of assembling and fastening them together. In the embodiment of my invention hereinbefore described the body portion is formed hollow in order to give 55 lightness combined with strength. The follower-head is made sufficiently massive and strong to withstand the blows of the pile hammer.

The operation of my apparatus is substantially as follows: The follower *a* is first placed upon the pile *g*, after the latter has been driven in the ordinary way to ground level; and then the pile and the follower are driven together, until the pile has reached 60 the required depth (Fig. 2). The pile hammer is then removed and the bore *d* of the follower is filled with cementitious material, such as soft concrete *h*. The follower is then gradually raised, concrete being 65 continuously poured into the bore *d* of the follower during the raising of the same. The concrete flows from the lower end of the follower as the latter is raised and fills the space *i* formerly occupied by the follower. 70 Where the cap is to be formed upon a pile under water (Fig. 3), the pile and the follower are driven below the river bed *j*, until the pile has reached the required depth, as 75 before. The remainder of the operation is 80 the same as described in connection with forming the cap after the manner illustrated in Fig. 2.

I claim:

A follower having a cap formed with an 85 aperture and adapted to receive the blows of the pile-hammer; a base-end formed with an aperture and having a recess adapted to receive the top of the pile; a tubular conduit the ends of which are fitted in said apertures; and a cylindrical body portion which connects the cap and the base-end and which is of substantially greater diameter than the pile to be driven.

Signed at the borough of Manhattan, city, 95 county and State of New York, this tenth day of April, in the presence of the two undersigned witnesses.

LEON PIERCE.

Witnesses:

ALPHONSE J. JAROT,
RUTH MORRIS.
